S D Vose Design for Stoves
No 130 *Patented June 26, 1847.*

Des. 130

Samuel D. Nose, Albany, New York.
Letters Patent. (Design No. 130. - I dated 26th June 1847.

The schedule referred to in these Letters Patent and making part of the same.

To all whom it may concern: Be it known that I, Samuel D. Nose of Albany, in the County of Albany, and State of New York, have invented or produced a new design for an air tight parlour stone, and I do hereby declare that the accompanying drawing making part of this specification, is a full and accurate representation of a stone after my said design, the sides not shewn in the drawing being similar to, and symmetrical with, those represented.

The ornaments are in the style of Louis XIV, and though not easily describable in words, are fully exhibited in the drawing.

What I claim as my invention and desire to secure by letters patent is, the combination and arrangement of ornamental figures and forms, represented in the accompanying drawing, forming an ornamental design for an air tight parlour stone.
